UNITED STATES PATENT OFFICE.

ERNEST S. KING, OF MINNEAPOLIS, MINNESOTA.

HEADLIGHT.

Application filed October 6, 1923. Serial No. 666,924.

To all whom it may concern:

Be it known that I, ERNEST S. KING, a citizen of the United States, residing at Minneapolis, in the county of Hennepin and State of Minnesota, have invented certain new and useful Improvements in Headlights, of which the following is a specification.

My invention relates to headlights, and more particularly to headlights for use on motor vehicles. Objects of the invention are to prevent the shaft of light which is projected from the headlight from being flashed into the eyes of pedestrians or occupants of approaching vehicles, and to intensify the light and concentrate the rays upon the roadway so that they will be directed in a lower plane, and will not diffuse upwardly, thereby aiding the driver of the motor vehicle.

The full objects and advantages of my invention will appear in connection with the detailed description, and the novel features of my inventive idea will be particularly pointed out in the claim.

In the accompanying drawings which illustrate several different forms in which my invention may be embodied, Fig. 1 is a view of one form of the invention in vertical longitudinal section. Fig. 2 is a view in section on the line 2—2 of Fig. 1. Fig. 3 is a plan view of the lens employed in this form of invention. Fig. 4 is a view of another form of the invention in vertical longitudinal section. Fig. 5 is a view of another form of the invention in vertical longitudinal section. Fig. 6 is a view of another form of the invention in vertical longitudinal section. Fig. 7 is a view of another form of the invention in vertical longitudinal section. Fig. 8 is a view in perspective showing the forms illustrated in Figs. 6 and 7. Fig. 9 is a view in perspective of the lens used in the form shown in Fig. 5. Fig. 10 is a view in perspective of the lens used in the forms shown in Figs. 6, 7, and 8. Fig. 11 is a view in cross section on the line 11—11 of Fig. 6. Fig. 12 is a view in cross section on the line 12—12 of Fig. 7. Fig. 13 is a fragmentary view showing a diffusing medium which may be employed.

In the form of invention shown in Figs. 1, 2, and 3, I provide a casing 14 in the front of which is secured a double convex lens 16. In the rear portion of this casing,

is a parabolic reflector 18 at the focus of which is placed a lamp 20. Secured adjacent the front of the reflector 18 is a lower mask 22, and an upper mask 24. These masks are opaque and preferably black in order not to reflect light. The lower mask 22 is in the form of a segment which covers nearly one-half of the opening of the reflector, while the upper mask 24 is in the form of a segment which is much smaller and covers only a small portion of the reflector opening. The inside of the lamp casing is of a dead black color in order not to reflect light. Rays of light emanating from the lamp 20 are reflected in parallel lines by the parabolic reflector 18, the rays reflected from substantially the lower half of the reflector being intercepted by the mask 22 while the rays reflected from the extreme upper edge 75 of the reflector are intercepted by the small mask 24. The rays which pass through the opening between the mask strike the lens 16 and all of those above the axial line will be refracted downwardly so as to strike the roadway in front of the headlight. As shown the lower mask does not cover quite one-half of the reflector opening which fact permits the device to be pointed slightly downwardly and still cause the upper edge 80 of the shaft of light to be horizontal, it being understood that the rays of light cross a short distance in front of the lens. The provision of the straight edges 26 and 28 for the masks causes the shaft of light to 85 be cut straight at top and bottom. In the form of invention shown in Fig. 4, the masks adjacent the front of the reflector such as just described are not employed, but the masking is obtained by providing part 90 of the reflector with a non-reflecting surface preferably by the use of a black coating. As shown, substantially the lower half of the reflector is provided with a black coating 30 which has a straight upper edge 32, and the extreme upper portion of the reflector 100 is provided with a black coating 34 which has a straight lower edge 36. By comparing Fig. 4 with Fig. 1, it will be seen that the effect on the rays of light is practically the same for both forms. In the form shown in Fig. 5, masks 22 and 24 similar to those shown in Fig. 1 are employed, but the opening between the masks is covered 105 with a piece of corrugated glass 38 such as shown in Fig. 13 which acts to diffuse the light. The front of the lamp casing

14 is provided with a lens 40 such as shown in Fig. 9. This lens thins down from the middle toward both the top and bottom and can be produced by cutting a round piece 5 from the double cylindrical lens shown in Fig. 10. In the forms thus far described, the casing 14 is cylindrical and may be used as an attachment to the cup-shaped member of the customary automobile headlight. In 10 the forms now to be described, a rectangular casing 14' such as shown in Fig. 8 is provided which requires a new rear portion for the headlight. In the form shown in Figs. 6 and 11, the front of the casing is provided 15 with a double cylindrical lens 42 such as shown in Fig. 10. Masks 22' and 24' similar to those shown in Fig. 1 are employed, the masks, however, being shaped to fit the rectangular casing. The opening between 20 the masks is covered with a piece of corrugated glass 38' similar to the piece 38 shown in Fig. 5, as being in engagement with the rear surfaces of the masks. In Fig. 6, the glass 38' is shown in engagement with the 25 front surfaces of the masks. In the form shown in Figs. 7 and 12, the parabolic reflector is dispensed with and the rear curved wall 44 is employed as the reflector. A lower horizontal partition 46 is placed directly 30 below the lamp 20, and an upper horizontal partition 48 is placed some distance above the lamp, and somewhat below the upper wall of the casing. These two partitions extend forwardly for a portion only 35 of the casing and are supported and held at their front ends respectively by strips 50 and 52 which in turn are supported by the casing. Attached to the front ends of the 40 partitions 46 and 48 and covering the space between the same, is a piece of white semi-transparent material 54 which may be composed of milky glass. It will be apparent that in all of the forms of invention described, the light reflected from the lamp

passes through the upper portion only of 45 the lens and is refracted downwardly at the same time so as to be thrown upon the roadway and below the level of the eyes of 50 pedestrians or occupants of other automobiles. It will also be apparent that the 55 shaft of light which is projected from the lamp is cut straight across at top and bottom, thus producing well-defined illumination 60 of the roadway. A spherical lens such as shown in Figs. 1, 3, and 4, is considered 65 the best form for use in connection with reflectors of the common type having continuous or uninterrupted surfaces, while a cylindrical lens such as shown in Figs. 5 to 10, is considered best for use in connection with 70 reflectors having interrupted surfaces such as are produced by providing the reflector with ridges.

I claim:

A headlight comprising a casing, a double 65 convex lens in the front of said casing, a parabolic reflector for the rear portion of said casing, a single source of light in said casing located at the focus of said reflector, a small opaque non-reflecting mask whose 70 upper edge is substantially in contact with the upper portion of the margin of said reflector whereby rays of light are prevented from passing thru the extreme upper portion of said lens, said mask having a lower 75 horizontally extending edge, and a large opaque non-reflecting mask substantially co-extensive with the lower half of said reflector and whose lower edge is substantially in contact with the lower portion of the margin 80 of said reflector whereby rays of light are prevented from passing through the lower portion of said lens, said large mask having an upper horizontally extending edge.

In testimony whereof I hereunto affix my 85 signature.

ERNEST S. KING
